UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

LASTING AND TACKING MACHINE.

1,007,051.

Specification of Letters Patent. Patented Oct. 31, 1911.

Application filed March 15, 1911. Serial No. 614,607.

To all whom it may concern:

Be it known that I, ARTHUR BATES, a subject of the King of Great Britain, residing at Leicester, Leicestershire, England, have invented certain Improvements in Lasting and Tacking Machines, of which the following description, in connection with the accompanying drawings, is a specification, like reference characters on the drawings indicating like parts in the several figures.

This invention relates to machines for use in the manufacture of boots and shoes and particularly to the lasting and nailing type of machines, although some features of the invention are useful also in fastening machines in which no lasting instrumentalities are included.

The invention will be explained in connection with a single pincer lasting machine of the type shown in United States Letters Patent No. 584,744.

The object of the invention is to expedite the work by the reduction of the number of operations necessary to complete the securing of the upper to the insole.

In a pincer-lasting machine it has been customary to drive one tack after each upper pulling operation of the pincer and it is now proposed that either one or more than one tack should at the will of the operator be driven to each upper pulling operation. This is particularly advantageous in that type of machine known as a single pincer-lasting machine for in this case the pincer is caused to grip the upper and move it over the shoe bottom where it is tacked and to repeat this operation progressively around the upper until the whole has been pulled and secured. Hence, in such a machine, at certain parts of the boot or shoe the space between the two successive grips of the pincer may be widened by the use of the present invention and consequently the time occupied in lasting the complete shoe may be reduced considerably.

Accordingly the invention comprises for a lasting machine having a pincer that operates successively on different portions of a shoe upper the combination with the pincer of a plurality of devices arranged to insert a plurality of fasteners along the edge of the shoe at each pulling operation of the

pincer, and means for rendering one or more of said devices inoperative.

55

According to one embodiment of this invention in a single pincer machine it is proposed to use a double raceway so that two tacks may be delivered together, and it is preferred to arrange it so that one tack may be delivered and driven centrally with regard to the pincer and the other may be delivered and driven to one side of the pincer although of course the tacks might be driven one on either side of the pincer. At the toe it is usual in this class of machine to give the pincer besides its ordinary upper pulling motion a lateral plaiting movement in order to form the necessary plait at those parts. When this is done it will be frequently unnecessary or inadvisable to drive a tack at more than one place, and consequently the invention also comprises the provision of means for simultaneously throwing into action the plaiting motion and preventing the delivery of a fastener from one of the raceways. It will be obvious that the raceway in use from which the fastener is to be delivered will be, in the case of the preferred construction, the one that is central relatively to the pincer—that is, it will not be the "offset" one. In the case where the nails are delivered and driven one on either side of the pincer the raceway in use will vary according to the direction of the plaiting movements of the pincer being preferably upon that side of it which may conveniently be termed the "following" side.

Conveniently the means for preventing the insertion of one of the fasteners and the means for giving the pincer a plaiting movement may be thrown into and out of operation by the same mechanism and at the same time because as a rule the said preventing means will be used only when the pincer is plaiting at the toe.

In some classes of work it may be desired to plait at portions of the side and still use the two tacks and in that case the said preventing means may be rendered inoperative by devices that are actuated by the movement of the edge gage or bunter into position for operating along the sides.

It has been found that in certain cases it is advisable that the spacing between adjacent fasteners should be varied, and this

is particularly the case at the heel and sides of the shoe.

Accordingly the present invention further comprises the provision for a pincer lasting 5 or like machine of a plurality of fastener drivers and means to vary the spacing between them.

According to a further feature there may be combined with these relatively adjustable drivers a plurality of fastener carriers 10 or throats and means to vary the spacing between them. Conveniently there may be operative connections such that adjustment between the drivers effects a corresponding 15 adjustment between the throats or vice versa.

According to one arrangement of the invention there may be automatic adjustment between the drivers and if desired there may 20 also be automatic adjustment between the throats, these adjustments being according to the requirements of the work or that part of the work which is being dealt with; and in a convenient construction this automatic 25 adjustment is obtained from a part of the machine which is adjusted according to the requirement of the work and in the embodiment of the invention about to be described this part of the machine is an edge 30 gage.

As herein shown the shoe bottom rest is improved in such a manner that it will adapt itself more readily to the surface of the insole and hold it more securely for the operation of the machine notwithstanding that the said surface is disposed somewhat out 35 of horizontal relationship to the machine. A work rest constructed according to this improvement also allows for tipping the 40 shoe to raise or lower the work surface at either side of the machine while still maintaining the bottom of the last in firm contact with the rest.

This invention can with particular advantage 45 be applied to a lasting machine equipped with the above described invention in which two tacks are inserted at each operation of the machine during the operation upon certain parts of the work as by its application 50 it is insured that both tacks are driven to a more equal extent. Accordingly a feature of this new shoe rest or work support for use in a lasting machine of the hand method type is that it is mounted to swivel laterally 55 for the purpose above set forth. Conveniently the shoe rest or work support mounted as above described may also be arranged to swivel at right angles to the swiveling motion first mentioned so as to compensate 60 for angular disposition longitudinally as well as for lateral displacement out of the horizontal. The swiveling action of the rest under the influence of changes in the level of the work surface may be utilized to effect 65 through suitable connections corresponding

changes in the levels to which the tacks are driven.

The invention will now be described as embodied in what is generally known as a "hand method" lasting machine, which is 70 a machine of the single pincer type, but it is to be understood that it is not limited to such a machine nor is it limited to the particular construction set forth for it is obvious that the construction of the various 75 parts and their relation to one another may be varied without going outside the scope of the invention.

Figure 1 is a side elevation of a machine equipped with the present invention; Fig. 2 80 is a fragmentary view of the reverse side of the machine; Fig. 3 is a plan view, partly in section, of certain parts shown in Figs. 1 and 2; Fig. 4 is a front view, partly in section, of the tacking devices; Fig. 5 is a side 85 sectional elevation of the raceway.

The machine comprises a column 2 on which is supported a head 4 that has bearings for the usual cam shaft. This shaft is provided with the usual complement of cams 90 for actuating the pincers, including the up-draw cam connected yieldingly to the up-draw lever from the front end of which the pincer 5 is suspended; the closing cam which operates through the usual rock shaft, 95 carried in the updraw lever for shutting the jaws upon the upper and holding them closed while the pincers are lifted to stretch the upper; and the overdraw cam acting through the stem of the overdraw yoke for moving the pincer inwardly from the edge 100 of the shoe bottom to carry the pulled upper into position to be fastened. One of the cams on the shaft also has the usual cam groove for oscillating the lever 6 which continuously actuates the rock shaft 8, said rock shaft having a head in which is adjustable a driver for moving the pincer laterally and turning it to effect the plaiting 110 movements which are needed for disposing of the surplus stock carried over the shoe bottom by the pincer at the toe and sometimes at other parts of the shoe. This driver is adjusted by the same mechanism as that shown in said patent, including the sleeve 115 10 which slides on the rock shaft and is moved by a knee lever connected to a vertical pivot attached to the post 2. All of these parts of the machine may be substantially as described and shown in full in said 120 patent and further description is therefore unnecessary in this specification.

The machine has in accordance with this invention, a double raceway 20 having two tack chutes 21 and 22 and associated with each of these chutes are the usual or suitable devices for separating and delivering tacks from each. The tacks are delivered to two tack holders 24, 25 the former of which is rigidly connected with the reciprocating 130

tack block supporting slide 26 of the commercial machine which is arranged and actuated by a cam on the cam shaft, as is fully disclosed in said prior patent. The 5 tack holder 24 has on its left hand side, Fig. 3, a lateral projection with which the tack holder 25 is pivotally connected for adjustment from and toward the holder 24 about a vertical axis. The tack holders are 10 formed on their lower faces to wipe or rub over the shoe bottom during their forward stroke for pressing the upper into position to be tacked and because of this function these tack holders are sometimes referred to 15 as reciprocating wipers. The tack holder 24 may have, as shown in Fig. 3, an end plate 28 which constitutes its most advanced upper rubbing portion and which is extended laterally across the space between 20 the two tack holders and across the front end of the holder 25 so as to present a continuous upper wiping surface at the front end of the two holders.

The tack driver bar 30 is movable endwise 25 in its guideway for driving tacks as and by the means described in said patent and has at its lower end a driver 32 coöperating with the tack holder 24. The driver bar has a lateral projection 34, Fig. 4, upon which is 30 pivoted an auxiliary driver bar 35 having a driver 36 coöperating with the tack holder 25, the pivotal connection between the bars 30 and 35 permitting the latter bar to be properly positioned laterally for alinement 35 with the driver passage in the tack holder 25.

As appears from Figs. 1, 4 and 5, there is a tack arresting finger 40 which has one end located over the lowermost tack in the tack chute 21 and which is mounted for pivotal 40 movement about a connection with the machine frame at 41 to engage said tack and thereby prevent further delivery of tacks from the chute 21. The second end of the finger 40 depends into the path of the cam 45 slide 42 in the right hand lateral face of which is a depression 43 between two high portions or surfaces. The spring 39 presses the finger toward the cam slide. The cam slide is connected by a vertical pivot 44 and 50 a spring pressed friction pin 45 with a rack bar 46. The rack bar is engaged by a segment toothed end of a lever 47 which comprises the two arms of the rock shaft 48, one arm being located substantially above the 55 other arm as appears from Fig. 1, and being connected by a vertical stud 49 to a lateral projection from the fork 50 which is attached to the upper end of the usual rocker of the machine which is connected downwardly 60 to the knee lever, all as fully shown in said prior patent. The purpose of this knee lever, rocker and fork, as fully described and illustrated in said patent, is to shift the sleeve 10 lengthwise of the rock 65 shaft 8 for adjusting the head of the rock

shaft or the driver through which the extent and direction of the upper plaiting movements are controlled. The details of this mechanism being well known and not of importance in connection with the present 70 invention are not necessary here to describe.

By reason of the connections from the fork 50 to the cam slide 42 it will be understood that the position of the finger 40 is controlled by the plaiter control. The cam 75 slide is so arranged with relation to the finger 40 that when no plaiting movement is being effected the lower end of the finger stands in or opposite to the depression 43 in the head of said slide but when the plaiting mechanism is thrown into action by turning the lever in one direction or the other, as may be required for plaiting one side or the other of the toe of the shoe, the cam slide will be shifted to bring one or the 80 other of the high portions of its head into engagement with the finger 40 and rock the latter into position and arrest the delivery of tacks from the chute 21. It may be here noted that the chute 22 and the tack holder 90 24 and driver 32 are positioned centrally with relation to the pincer while the chute 21, holder 25 and driver 36 are offset with relation to the pincer and that it is the delivery of the offset tack which is discontinued when the plaiting mechanism is rendered operative. This arrangement provides one tack only for each operation of the pincers around the toe of the shoe and for driving that tack centrally with relation 95 to the plait formed by the pincers as is known in the use of this type of machine, while two tacks are driven for each operation of the pincers when the plaiting mechanism is not in use. Considered with reference to the direction of progress of lasting, the offset tack is advantageously on the following side of the pincers, that is, the direction of progress is such that the offset tack is driven in the space between the central tack 100 and the last tack inserted by the previous cycle of operation of the machine.

The pivotal connection 44, 45 permits a limited swinging movement of the cam slide 42 on the rack bar 46 which is sufficient to 115 render the cam slide ineffective for rocking the finger 40 and stopping the delivery of tacks when no supplemental means is operative for preventing the relative pivotal movement of the cam slide and rack bar. 120 For the purpose of providing this means the usual bunter edge rest 60 of the machine which slides forwardly and backwardly in a fixed track as indicated by full and dotted lines in Fig. 1 has a spring pressed pin 62 125 which in the forward or operative position of the bunter edge rest engages a depending flange 63 of the cam slide 42 and holds it out toward the lower end of the finger 40 as is clearly shown in Fig. 4. The bunter edge 130

rest occupies its advanced operative position during the lasting of the toe and of the heel but this rest, on account of its thickness, must be moved backwardly into an inoperative position in order to allow the shoe to be so presented to the machine that the shank can be lasted. As a matter of practice, operators shift the thick edge rest to its inoperative position for lasting the shank and also the sides and in doing so expose for use the thin edge rest 61 which is immovably supported directly over the thick rest and is so shaped that it offers no obstruction to the presentation of the shank and side portions of the shoe to the machine. It will now be seen that while lasting the shank and sides of the shoe the cam slide 42 is not held to its work and that therefore the plaiting mechanism can be thrown into operation, as is sometimes desired in lasting around the forepart or corner of a deeply incurved shank, without stopping the delivery of the offset or second tack. The thick edge gage or rest 60 is also herein connected to devices which control the lateral position of the tack holder 25 and driver 36 with relation to the holder 24 and driver 32 thereby controlling the spacing of the two tacks. To this end the thick gage carrier has rack teeth 65 on an upper edge face, or a rack bar is attached to said gage carrier, and the teeth mesh with a pinion 66 which is fast on a shaft 68 that turns in the machine head and has a threaded end as shown best in Fig. 3. The threaded end of the shaft turns in a nut that is secured to the rear end of a lever 70 the hub of which turns in bearings in the machine head and the front arm of which is formed with a slot that extends from the center of oscillation of the lever radially and is as long as, or longer than, the usual length of reciprocatory movement of the tack holders 24, 25. There is erected on the side of the tack holder 24, or on the tack block supporting slide 26, bearing for a vertical rock shaft 75 the lower end of which shaft may conveniently serve as the pivoted carrier upon which the tack holder 25 is fastened for movement laterally from and toward the holder 24. The lower arm of the rock shaft extends backwardly and has a stud standing in the slot in the lever 70 whereby, as the tack holder and its supporting slide are reciprocated in and out, the rock shaft is turned in proportion to the angularity of the slot in the lever 70 with relation to the path of the tack holder 24 and supporting slide 26. The location of the slot in lever 70 by which it extends from the axis of the lever provides for returning the tack block 25 always to a predetermined lateral relation to the tack block 24 and to the tack raceway and the chute 21 from which the holder 25 receives its tack. This tack receiving position will not be altered

by any adjustment of the lever 70 by the edge gage and this is an important feature of the construction. An upper arm of the rock shaft 75 engages the head of the sliding block 80 which is normally held against said arm by a spring pressed plunger 82. The block 80 has a forwardly projecting stud carrying a roll that stands in a groove in the rear face of the driver bar 35. Through this connection with the driver bar 35 said bar is swung about its pivotal connection with the bar 30 and adjusted laterally in company with the tack holder 25.

The above described arrangements are such that when the thick edge rest occupies its retracted position shown in dotted lines in Fig. 1, which is the position for lasting the shank and sides of the shoe, and is that position in which two tacks are driven uninterruptedly without regard to the plaiting mechanism, as above described, the lever 70 will occupy its position of greatest angularity with reference to the direction of reciprocation of the tack block 24 and slide 26. The tack block 25 will then advance in each operation of the machine from its constant tack receiving position under chute 21 and be moved toward the left in Figs. 3 and 4 to a position for driving the offset tack spaced widely from the tack that is inserted from holder 24. It will then return to its constant tack receiving position, the roll on the lower arm of the rock shaft 75 standing centrally with relation to the axis of the lever 70. When the thick edge gage is adjusted to its forward position for lasting the heel of the shoe it will effect through rack teeth 65, pinion 66 and screw 68 an adjustment of the lever 70 to position said lever with its slotted arm more nearly parallel with the direction of reciprocation of the tack holder 24 and slide 26 and therefore, while the edge rest remains forward, the rock shaft 75 will receive a short oscillation and the tack holder 25 will thereafter be spaced in its tack driving position at a less distance than formerly from the holder 24. Through the upper arm of the rock shaft 75 the tack driver 36 is adjusted in company with its tack holder 25. This arrangement provides for driving the tacks relatively closer together at the heel seat than at the sides of the shoe. The spacing of the tacks may be initially determined by adjustment of the shaft 68 with relation to the pinion 66. For this purpose the pinion may be held normally fast on the shaft by a screw 67 which can be loosened to permit movement of the shaft independently of the pinion. The shoe bottom rest is carried by a bracket located in front of the pincers and comprises an arm 90 which is formed with a bearing for a rod 92 that can turn about an approximately horizontal axis extending from front to back of the machine. On the inner end of this rod the

bottom rest foot 94 is mounted to turn about a horizontal axis 95 which extends transversely of the first mentioned axis. This mounting for the bottom rest foot permits the foot to turn in any direction necessary to adapt itself to the level of the work or the angular position which the particular portion of the work engaged by it may occupy. This arrangement provides for such relative adjusting movement of the rest and two drivers as enables the operator to obtain insertion of the two tacks from the tack holders to the same depth.

In the use of the machine the operator will proceed in accordance with his usual custom in lasting shoes upon this well known commercial type of machine. Ordinarily the shanks and sides are lasted first and for this purpose the thick edge rest is pushed back to expose the thin edge rest. By this adjustment of the thick edge rest the tack holders and drivers are spaced wide apart and the plunger 62 is withdrawn from the cam slide 42. The machine then proceeds to drive after each pulling movement of the pincer, two tacks, one of which is located centrally with relation to the pincer and the other of which is offset laterally therefrom. The insertion of the offset tack will not be interrupted by throwing the plaiting mechanism into use at any time that that may be needed. When the shanks and sides of the shoe have been lasted the thick edge gage will be returned to its operative position. This adjustment will change the angular position of the lever 70 and cause the tacks to be spaced nearer together. It will also, by means of the plunger 62, press the cam slide 42 into position to cause delivery of tacks from the chute 21 to be stopped whenever the plaiting mechanism is thrown into operation. It is a very advantageous characteristic of the described construction that the operator may obtain wide or narrow spacing of the tacks as may be best suited to the portion of the shoe which he is lasting and may discontinue the insertion of one of the tacks while plaiting the toe without being obliged to give any special attention to these adjustments or to make any manipulation of the machine in addition to those to which he is accustomed. He is also enabled by the driving of two tacks for each operation of the pincers to last the sides and the heel of the shoe by a substantially smaller number of machine cycles than heretofore and therefore in a materially shorter time than is required by machines not equipped with this invention.

Having explained the nature of this invention, I claim as new and desire to secure by Letters Patent of the United States:

1. A lasting machine having, in combination, a pincer and mechanism for actuating it to seize, pull and release the up-

per and a tacker coöperating therewith to fasten the pulled upper, said machine having provision for adjustment to cause the tacker to insert a plurality of tacks or a single tack alternatively for each cycle of 70 the pincers.

2. A lasting machine having, in combination, a pincer and mechanism for actuating it to seize, pull and release the upper and a tacker coöperating therewith to fasten the pulled upper, said tacker being constructed and arranged to drive two tacks, and having provision for suspending at the will of the operator the insertion of one of the two tacks.

3. A lasting machine adapted for working upon different parts of the upper successively in repeated operations of the machine having, in combination, a pincer to seize and pull the upper, a tacker capable of inserting two tacks for one upper pulling operation whereby the space between two successive grips of the pincer may be widened, and means capable of adjustment by the operator to cause insertion of one of 90 the two tacks to be discontinued at parts of the shoe where the upper pulling operations require to be close together.

4. A lasting machine adapted for working upon different parts of the upper successively in repeated operations of the machine having, in combination, a pincer to seize and pull the upper, a tacker, and means adapted for adjustment as different parts of the shoe are being lasted to cause one or 100 two tacks to be inserted alternatively as the operator may desire for each grip of the pincers.

5. A lasting machine adapted for working upon different parts of the upper successively in repeated operations of the machine having, in combination, a pincer to seize and pull the upper, and a tacker arranged to insert one tack in front of the pincer and another at the following side of 110 the pincer.

6. A lasting machine adapted for working upon different parts of the upper successively in repeated operations of the machine having, in combination, a pincer to seize and pull the upper, a tacker arranged to insert one tack in front of the pincer and another at the following side of the pincer, and means for causing the insertion of the latter tack to be discontinued at times.

7. A lasting machine having, in combination, a pincer that operates successively on different portions of a shoe upper, a plurality of devices arranged to insert a plurality of fastenings along the edge of the 125 shoe at each pulling operation of the pincer, and means for rendering one of said devices inoperative.

8. A lasting machine having, in combination, a pincer that operates successively on 130

- different portions of a shoe upper, a plurality of raceways, and a plurality of tack driving devices to receive from the raceways and insert a plurality of tacks at each pulling operation of the pincer, said parts being arranged so that one tack is driven centrally with regard to the pincer and the other to one side of the pincer.
9. A lasting machine having, in combination, a pincer that operates successively on different portions of a shoe upper, a plurality of raceways, and a plurality of tack driving devices to receive from the raceways and insert a plurality of tacks at each pulling operation of the pincer, and means adjustable by the operator to stop the delivery of tacks from one of the two raceways while delivery is continued from the other raceway.
10. A lasting machine having, in combination, a pincer that operates successively on different portions of a shoe upper, means to give the pincer upper plaiting movements, a plurality of devices arranged to apply a plurality of fastenings along the edge of the shoe at each pulling operation of the pincer, and means for automatically rendering one of said devices ineffective when the grippers have plaiting movements.
11. A lasting machine having, in combination, a pincer that operates successively on different portions of a shoe upper, means to drive one tack centrally with regard to the pincer and another offset to one side of the pincer at one pulling operation of the pincer, and means to give to the pincer upper plaiting movements and to cause the driving of the offset tack to be discontinued while the pincer has plaiting movements.
12. A lasting machine having, in combination, a pincer that operates successively on different portions of a shoe upper, means to give the pincer a plaiting movement at times, a tacker, and connections for automatically rendering the tacker inoperative when the pincer has plaiting movements.
13. A lasting machine having, in combination, a pincer that operates successively on different portions of a shoe upper, means to give the pincer a plaiting movement at times, a tacker, a raceway, and connections for automatically discontinuing delivery of tacks from the raceway when the plaiting movements are given to the pincer.
14. A lasting machine having, in combination, a pincer that operates successively on different portions of a shoe upper, means to give the pincer a plaiting movement at times, a tacker, a raceway, and means for simultaneously throwing into action the plaiting motion and preventing the delivery of a tack from the raceway.
15. A lasting machine having, in combination, a pincer that operates successively on different portions of a shoe upper, means to give the pincer a plaiting movement at times, a tacker, a raceway, and means for simultaneously throwing into action the plaiting motion and preventing the delivery of a tack from the raceway, said machine having provision for rendering the preventing means ineffective upon adjustment of another part of the machine.
16. A lasting machine having, in combination, a pincer that operates successively on different portions of a shoe upper, means to give the pincer a plaiting movement at times, a tacker, a raceway, means for simultaneously throwing into action the plaiting motion and preventing the delivery of a tack from the raceway, an edge gage that must be moved to an inoperative position while the shank is being lasted, and connections from the edge gage to render the preventing means ineffective while the shank is being lasted whether or not the plaiting movement is used.
17. A lasting machine having, in combination, a pincer that operates successively on different portions of a shoe upper, means to give the pincer a plaiting movement at times, a tacker, a raceway, a finger located near the lower end of the raceway and pivoted so that it can be brought into contact with the head of the last tack in the raceway, a separator into the path of which the finger prevents the tack from moving, and connected means for initiating the plaiting movements of the pincer and cause the finger to engage the last tack, substantially as described.
18. A lasting machine having, in combination, a pincer, means to actuate it, additional means to cause plaiting movements to be given to the pincers including a rocker, and a sleeve to shift the connection from the rocker to the pincer, a raceway, a tacker, and a connection from said sleeve to cause the delivery of tacks from the raceway to be controlled automatically with the plaiting movements.
19. A lasting machine having, in combination, a pincer, means to actuate it, additional means to cause plaiting movements to be given to the pincers including a rock shaft 8, the sleeve 10 shiftable thereon; the lever 47 connected to the sleeve, and the tack controlling finger 40 arranged to be actuated by said lever.
20. A lasting machine having, in combination, a pincer, means to actuate it, additional means to cause plaiting movements to be given to the pincers including a rock shaft 8, the sleeve 10 shiftable thereon in either direction from a central position to cause the plaiting movements to be begun and to determine their direction, a tack raceway, a tack controlling finger, and a rack bar arranged to be actuated with said sleeve and having a cam face formed as two high por-

- tions with a depression between them into which the finger seats and from which it is moved when the sleeve is shiftable to cause plaiting in one or the other direction.
21. A lasting machine having, in combination, a pincer, means to actuate it, additional means to cause plaiting movements to be given to the pincers, a raceway, a tacker, an adjustable edge gage, means to start the 5 plaiting movements and stop the delivery of tacks from the raceway when the edge gage is in one position, said means being inoperative to stop delivery of tacks when the edge gage is in a different position.
22. A lasting machine having, in combination, a pincer, means to actuate it, additional means to cause plaiting movements to be given to the pincers, a raceway, a tacker, an adjustable edge gage, a manually shiftable 10 member 10 and connections to start the plaiting movements, and a connection therefrom to the raceway to stop delivery of tacks, said latter connection including the rack bar 46 and cam bar 42 pivoted together and 15 held in alignment and operative by the edge gage when the latter is forward.
23. A lasting machine having a pincer that operates successively on different portions of a shoe upper, and, in combination, 20 with the pincers, two drivers, two raceways and two separators arranged to insert two fastenings along the edge of the shoe at each pulling operation of the pincer, and means for preventing the delivery of a fastening 25 from one of the raceways at a predetermined time in the operation of the machine on the shoe.
24. A lasting machine having a pincer that operates successively on different portions of a shoe upper and, in combination 30 with the pincer, two drivers, two raceways and two separators arranged to insert two fastenings along the edge of the shoe at each pulling operation of the pincer, and means 35 for varying the spacing between the fastenings at predetermined times in the operation of the machine.
25. A lasting machine that operates successively on different portions of a shoe edge 40 and having in combination, a plurality of devices arranged to insert a plurality of fastenings along the edge of the shoe at each operation and means controlled by the operator for preventing the insertion of one of 45 the said plurality of fastenings.
26. A lasting machine that operates successively on different portions of a shoe edge and having, in combination, two drivers, two raceways and two separators arranged to 50 insert two fastenings along the edge of the shoe at each operation, and means controlled by a knee lever for preventing the delivery 55 of fastenings from one of the raceways to the separator and the driver that are associated with that raceway.
27. A lasting machine having, in combination, a pincer that operates successively on different portions of a shoe upper, a plurality of devices arranged to insert a plurality of fastenings along the edge of the shoe at each pulling operation of the pincer, and means for varying the spacing between such fastenings.
28. A lasting machine having, in combination, a pincer that operates successively 70 on different portions of a shoe upper, two tack drivers, and two tack holders arranged to insert two tacks for each pulling operation of the pincer, and means for varying the spacing between the drivers and between the holders.
29. A lasting machine having, in combination, a pincer that operates successively 75 on different portions of a shoe upper, two tack drivers, and two tack holders arranged to insert two tacks for each pulling operation of the pincer, means for adjusting one driver away from the other, and operative connections such that adjustment of the driver effects a corresponding adjustment of 80 the associated holder.
30. A lasting machine having, in combination, a pincer that operates successively 85 on different portions of a shoe upper, a plurality of devices arranged to insert a plurality of fastenings along the edge of the shoe at each pulling operation of the pincer, an edge gage that is adjustable to different positions, and connecting mechanism between said gage and said devices to vary 90 the spacing between the fastenings when the gage is shifted.
31. A lasting machine having, in combination, a pincer that operates successively 95 on different portions of a shoe upper, a plurality of devices arranged to insert a plurality of fastenings along the edge of the shoe at each pulling operation of the pincer, a movable edge gage, and connections to one 100 of said devices to change the spacing between the fastenings upon movement of the gage.
32. A lasting machine having, in combination, a pincer that operates successively 105 on different portions of a shoe upper, a plurality of devices arranged to insert a plurality of fastenings along the edge of the shoe at each pulling operation of the pincer, a plurality of relatively movable edge gages, and means actuated by relative movement of 110 said gages to shift one of the fastening inserting devices relatively to the other.
33. A lasting machine having, in combination, a pincer that operates successively 115 on different portions of a shoe upper, a plurality of devices arranged to insert a plurality of fastenings along the edge of the shoe at each pulling operation of the pincer, two gages arranged to be used alternatively, 120 and connections with said devices whereby 130

when one gage is used the fastenings will be driven one distance apart and when the other gage is used the tacks will be driven a different distance apart.

34. A lasting machine having, in combination, a pincer that operates successively on different portions of a shoe upper, a plurality of devices arranged to insert a plurality of fastenings along the edge of the shoe at each pulling operation of the pincer, a device which is adjusted according to the requirements of that portion of the work which is being dealt with as the lasting proceeds around the shoe, and connections from said adjustable device to the inserting devices to effect automatically a spacing of the fastenings which is appropriate for the portion of the work being dealt with.

35. A lasting machine having, in combination, two gages arranged to be used alternatively, means for driving two tacks at once, and a device controlling the operation of said driving means and gages whereby when one gage is operative the two tacks will be driven one distance apart and when the other gage is operative the two tacks will be driven a different distance apart.

36. A lasting machine having, in combination, a stationary edge gage and a relatively movable edge gage, holders and drivers for inserting two tacks at the same time, and means actuated by a movement of the movable gage for causing adjustment of said holders and drivers to change the spacing of the tacks.

37. A lasting machine having, in combination, a thick edge gage for use at the heel of the shoe, a thin edge gage for use at the shank of the shoe, means permitting movement of the thick edge gage toward and from operative position, tack driving devices arranged to insert two tacks at once, and means actuated by a movement of said thick gage for causing the spacing between the said tacks to be varied.

38. A lasting machine having, in combination, a thick edge gage for use at the heel of the shoe, a thin edge gage for use at the shank of the shoe, said thick gage being movable to a retracted position for shank lasting, tack driving devices arranged to insert two tacks side by side along the edge of the shoe, and spacing connections controlled by said thick gage to cause the tacks to be inserted close together around the heel and farther apart along the shank.

39. A lasting machine having, in combination, a thick edge gage for use at the heel of the shoe, a thin edge gage for use at the shank of the shoe, said thick gage being movable to a retracted position for shank lasting, tack driving devices arranged to insert two tacks side by side along the edge of the shoe, a pincer having plaiting movements for lasting the toe, and connections

from the edge gage and from the pincers mechanism to the tackers to cause narrow spacing of the tacks when the thick gage is operative and to discontinue the driving of one of the two tacks when the pincers are plaiting the toe of the shoe.

40. A lasting machine having, in combination, a driver bar that has a lateral extension, a second driver bar pivoted to the extension to move toward or from the first driver bar in accordance with the spacing of tacks that is desired, and means connected with the first bar for actuating the two bars to insert the tacks.

41. A lasting machine having, in combination, a driver bar that has a lateral extension, a second driver bar pivoted to the extension to move toward or from the first driver bar in accordance with the spacing of tacks that is desired, means for effecting adjustment of the second driver bar, and means connected with the first bar for actuating the two bars to insert the tacks.

42. A lasting machine having, in combination, a driver bar that has a lateral extension, a second driver bar pivoted to the extension to move toward or from the first driver bar in accordance with the spacing of tacks that is desired, a sliding block working in a recess in the second bar for guiding said bar, and means for moving said sliding block laterally to effect a shift of the second bar.

43. A lasting machine having, in combination, a driver bar that has a lateral extension, a second driver bar pivoted to the extension to move toward or from the first driver bar in accordance with the spacing of tacks that is desired, a sliding block working in a recess in the second bar for guiding said bar, a rock shaft with which said block has operative connection, an adjusting lever having a radial slot in one arm to receive an end of an arm of the rock shaft, and an adjustable edge gage having connection with the other arm of said lever to control the spread of the driver bars in accordance with the position of the edge gage.

44. A lasting machine having, in combination, a driver bar, a second bar pivotally connected thereto, a rock shaft having one arm in sliding connection with the second bar and an adjustable edge gage having connection with the other arm of the rock shaft to control spread of the drivers according to the position of the edge gage.

45. A lasting machine having, in combination, a driver bar, a second bar pivotally connected thereto, a rock shaft having one arm in sliding connection with the second bar and an adjustable edge gage having connection with the other arm of the rock shaft to control spread of the drivers according to the position of the edge gage, a tack

- holder for the first driver bar, a second tack holder for the second bar, and a connection from said edge gage to said second holder to adjust it with said second bar.
5. 46. A lasting machine having, in combination, a tack holder, a second tack holder, an adjustable edge gage and connections from said gage to the second tack holder to adjust it relatively to the first holder.
10. 47. A lasting machine having, in combination, two relatively adjustable driver bars having an in and out and a tack driving movement, means for supplying tacks to be driven thereby, a sliding edge gage, a screw arranged to be turned by the movement of the edge gage, a lever adjusted by such screw movement and having a radial slot in one arm, and a rock shaft which partakes of the in and out movement of the bars and has one arm connected with one bar and the other arm in said radial slot whereby to position the connected driver bar relatively to the other bar in accordance with the position of the edge gage.
15. 48. A lasting machine having, in combination, two relatively adjustable reciprocating tack holders, an adjustable edge gage, a screw connected to be turned by the gage, a lever adjusted by the screw and having in one arm a radial slot, a rock shaft partaking of the reciprocating movement of the tack holders and having one arm in said slot and the other connected to one of the holders to return the adjustable tack holder to a predetermined relation to the other holder by the backward reciprocation and spread the adjustable holder away from the other holder by the forward stroke a distance which varies according to the position of the edge gage.
20. 49. A lasting machine having, in combination, two reciprocating tack holders that are relatively adjustable laterally to space tacks, and means for returning them to a uniform tack receiving relation and projecting them to different laterally spaced tack delivering relations.
25. 50. A lasting machine having, in combination, two reciprocating tack holders that are relatively adjustable laterally to space tacks, and means acting automatically as the holders are reciprocated to return them to constant relation and to project them to relations which can be varied according to the tack spacing required.
30. 51. A lasting machine having, in combination, a tack holder, means for reciprocating it, a guide for controlling the direction of the reciprocation, and means to adjust said guide to cause the holder to reciprocate in different directions.
35. 52. A lasting machine having, in combination, a tack holder, a tack driver, means to reciprocate the holder and the driver out and in for the purpose described, a guide for controlling the directions of the reciprocations, and means to adjust said guide to cause the holder and driver to be reciprocated in varying directions.
40. 53. A lasting machine having, in combination, two tack holders, two tack drivers, means to reciprocate said holders and drivers between tack receiving and tack driving positions, a guide having control of the direction in which one holder and driver shall reciprocate relatively to the other, and means to adjust said guide to cause said holder and driver to go to driving positions that are spaced different distances from the other holder and driver.
45. 54. A lasting machine having, in combination, a combined tack holder and wiper, reciprocating means therefor, an edge gage adjustable from and toward the front of the machine, a guide for said combined tack holder and wiper to control the direction of its reciprocatory movement, and a connection between said guide and said edge gage by which adjustment of the gage adjusts the guide to vary said direction of reciprocation.
50. 55. A lasting machine having, in combination, a reciprocatory wiper, means for actuating it, a guide for controlling the direction of the wiper movement, an adjustable edge gage, and a connection between the gage and the guide for adjusting the latter to cause the wiper to reciprocate in different angular directions according to the position of the gage.
55. 56. A lasting machine having, in combination, a pincer, a pair of drivers and associated parts for inserting two tacks laterally spaced along the edge of a shoe bottom for each pulling movement of the pincers, means for adjusting the spacing between the tacks, a shoe bottom rest, and means permitting relative adjusting movement of the rest and the two drivers to facilitate like depths of insertion for the two tacks on the portions of the shoe bottom which are uneven.
60. 57. A lasting machine having, in combination, two adjacent, laterally reciprocating wipers, means for actuating the wipers, and means bridging the space between the two wipers to present therewith a continuous upper wiping surface.
65. 58. A lasting machine having, in combination, a reciprocating wiper, a second wiper arranged adjacent to the first and adjustable relatively thereto, and a member attached to the first wiper bridging the space between the wipers and extending across the front end of the adjustable wiper to present a continuous end face for said wipers.
70. 59. A lasting machine having, in combination, the reciprocating tack holder and wiper 24, the tack holder and wiper 25 movable forwardly and backwardly with the member 24 and having also movement from

a constant tack receiving relation to the member 24 into a variable tack delivering relation to said member 24 for spacing the tacks different distances apart, and the upper wiping plate 28 attached to the front end of the member 24 and extending laterally in front of the member 25 for the purposes described.

60. A lasting machine having, in combination, a pincer, an adjustable edge gage and a tacker arranged to insert a plurality of tacks at each operation of the pincer and arranged to have the spacing between the tacks varied by the adjustment of the edge gage.

61. A lasting machine having, in combination, a pincer, operating mechanism therefor arranged for adjustment, tack driving means adapted to insert a plurality of tacks for each operation of the pincer and arranged to have the number of tacks inserted varied by the adjustment of the pincer operating mechanism.

62. A machine of the class described having, in combination, lasting means for operating successively upon different portions of a shoe upper, means for inserting a plurality

of fastenings for each lasting operation, and means for varying the spacing between the fastenings.

63. A machine of the class described having, in combination, lasting means for operating successively upon different portions of a shoe upper, means for inserting a plurality of fastenings for each lasting operation, and means for varying the spacing between the fastenings at predetermined times in the operation of the machine.

64. A machine of the class described having, in combination, lasting means for operating successively upon different portions of the upper, means for inserting a plurality of fastenings at each lasting operation, and means for discontinuing the insertion of one of said fastenings, at will.

In testimony whereof I have signed my name to this specification in the presence of two subscribing witnesses.

ARTHUR BATES.
